UNITED STATES PATENT OFFICE.

ORIN L. LEWIS AND JOSEPH W. MOON, OF TOMPKINS, MICHIGAN.

REVERSE-VALVE MECHANISM FOR STEAM-ENGINES.

1,123,902.

Specification of Letters Patent.

Patented Jan. 5, 1915.

Application filed October 10, 1913. Serial No. 794,533.

To all whom it may concern:

Be it known that we, ORIN L. LEWIS and JOSEPH W. MOON, citizens of the United States, residing at Tompkins, in the county of Jackson and State of Michigan, have invented certain new and useful Improvements in Reverse-Valve Mechanism for Steam-Engines; and we do hereby declare the following to be a full, clear, and exact description of the invention, such as will enable others skilled in the art to which it appertains to make and use the same.

This invention relates to reverse gear mechanism for steam engines and one of the principal objects thereof is to provide a valve for reversing a steam engine.

Another object thereof is to provide a reversing valve situated between the valve seat of the slide valve and the top of the cylinder.

Another object thereof is to provide a reversing valve which may be positively operated by means of a single direct acting valve rod.

These and other objects may be attained by means of the construction, combination, and arrangement of parts, hereinafter more fully described and claimed, and illustrated in the accompanying drawing in which;

Figure 1, is a longitudinal vertical sectional view taken through the steam chest and cylinder of a locomotive, showing the reversing valve arranged therein. Fig. 2, is a top plan view showing the steam chest in dotted lines and the slide valve removed. Fig. 3, is a view similar to Fig. 2, showing the slide valve seat removed. Fig. 4, is a view similar to Fig. 2, showing the reversing valve removed.

In the embodiment illustrated, the cylinder 1 is shown with the cylinder heads removed and is provided on the top thereof with the usual steam chest 2 having a top 3 thereon secured in the usual manner. As shown the top of the cylinder 1 is slightly raised as at 4 at the central portion thereof to provide a seat for the reversing valve 5 which is circular in formation and provided on one side thereof with an outwardly extending lug 6, to the outer end of which is pivoted one end of a link 7, the other end of the link being pivoted to one end of the valve rod 8. As shown, the inner end of the link 7 is provided with a downwardly extending lug 9 for engaging with an opening in the outer end of the lug 6, the outer end

of the link 7 being curved downwardly and outwardly and pivoted by a bolt 10 to the valve rod 8. This rod enters the steam chest at a point near the lower side thereof and to one side of the center thereof, through a packing box 11, of any preferred construction. The valve 5 has formed in this upper face a pair of oppositely disposed semi-circular grooves 12 and 13 spaced from the outer periphery of the valve by the walls 14 and having their ends separated by the walls 15 and 16. Extending vertically through the body of the valve 5, adjacent the wall 16, is a valve opening 17 and a corresponding opening 18 is provided adjacent the wall 15, said openings being diametrically opposed and of a substantially wedge shape. As shown the lower side of the valve 5 is perfectly plain and rests against the valve seat 4 for rotation thereon.

The cylinder 1, is provided with the usual steam ducts 19 and 20 extending in the upper wall of the cylinder, from the valve seat 4 in opposite directions to points adjacent the ends of the cylinder 1, in a well known manner. The upper wall of the cylinder is provided centrally of the valve seat 4 with a circular socket 21 extending from the valve seat to a point near the bore of the cylinder and connecting at its lower end with the exhaust duct 22, thus forming an exhaust port for the cylinder. Seated for rotation in the socket is a stem 23 formed integral with the valve 5, and extending downwardly to a point level with the upper edge of the exhaust duct 22. The upper side of the valve 5 is formed with a sleeve 24 integral with the valve, and forming therewith a shoulder 25 which co-acts with the walls 14 for supporting the slide valve seat 26, the said sleeve being seated for rotation in a circular opening centrally of the valve seat 26 and having its upper end flush with the upper face of said valve seat. Extending vertically through the sleeves 24 and 23 and through the body of the valve 5, is a bore 27 communicating at its lower end with the duct 22, and at its upper end with the slide valve 28, thus forming a conduit through which steam from the cylinder may be exhausted.

The slide valve seat 26 abuts at its corners against the enlarged corners 29 of the steam chest 2 and is secured to pins 30 extending upwardly from the bottom of the steam chest. The slide valve 28 is of the usual well

known construction and is provided with the usual valve stem 31 extending through a packing box 32 in the steam chest, which may be of any well known construction but which is here shown as providing a threaded lug 33 having its outer end beveled inwardly; and a threaded cap 34 secured on the lug 33 and provided with an oppositely disposed inwardly beveled face between 5 which and the beveled end of the lug 33, is situated the packing 35. The packing box 10 11 is formed in the same manner.

The upper face of the valve seat 4 is provided with the oppositely disposed curved 15 grooves 36 and 37 situated immediately below and corresponding in shape and contour with the slots 12 and 13 in the valve 5, and connect at points 38 and 39 with the inner ends of the steam ducts 19 and 20 respectively. The walls 40 and 41 corresponding 20 with the walls 15 and 16 of the valve 5, separate the ends of the slots in the valve seat 4. When the valve 5 is positioned as shown in Figs. 1 and 3, the steam passes 25 through a slot opening 42 in the forward end of the slide valve seat 26 down into the slot 12 of the valve 5, down through the opening 17 therein, through the slot 37 in the valve seat 4, and thence through the duct 20 into 30 the rear end of the cylinder 1. Upon the return of the piston (not shown) toward the forward end of the cylinder, steam which has previously been admitted into that end, is exhausted up through the duct 19 into and 35 through the slot 36 in the valve seat 4, up through the opening 18 in the valve 5, through the slot 13 therein, up through the opening 43 in the rear end of the valve seat 26 and corresponding with the opening 42 40 therein, under the slide valve 28, down through the bore 27 in the valve 5 and out through the exhaust duct 22. Upon pulling the rod 8 backwardly the valve 5 is rotated rearwardly thus registering the 45 opening 18 in the valve with the slot 37, in the valve seat instead of the slot 36 therein, and registering the opening 17 in the valve with the slot 36 in the valve seat 4 instead of the slot 37 therein, thus 50 causing the steam to first enter the forward end of the cylinder when the slide valve 28 is positioned as shown, instead of the rear end of the cylinder and thus reversing the engine, the exhausted steam finding its way 55 out through the duct 20 instead of through the duct 19 as when the valve is in the position shown. Steam is admitted into the steam chest above the valve seat 26 and on the outside of the slide valve 28 in any well known manner (not shown).

It will be noticed that the shape of the openings 18 and 17 in the valve 5 corresponds exactly with the walls 40 and 41 in the valve seat 4, so that when the valve is rotated half way the walls 40 and 41 will

close the openings 18 and 17 thus making it impossible for steam to be admitted into the cylinder without shifting the valve in one direction or the other. As is obvious, when the valve is in the neutral position and the 70 openings 18 and 17 are closed, the engine cannot be run.

Although we have described the preferred embodiment of our invention we reserve, and may exercise, the right to make such changes 75 in the construction, combination, and arrangement of parts as do not depart from the spirit of the invention and the scope of the appended claims.

We claim:

1. In a reversing valve mechanism for steam engines the combination with a piston cylinder having a socket formed in the top thereof, of oppositely disposed arcuate inlet and outlet ports formed in the top of 85 said cylinder in proximity to said socket, ducts communicating with said ports and said cylinder at the opposite ends of the latter, a slide valve seat spaced from the top of said cylinder and having inlet and outlet 90 ports in alignment with first named ports, a rotary disk valve positioned between said cylinder and said slide valve seat for controlling the communication between the two sets of ports and an integral stem 95 formed on said disk valve to rotatably seat the same in said socket.

2. In a reversing valve mechanism for steam engines the combination with a piston cylinder having a socket formed in the top 100 thereof, and an exhaust port communicating with said socket of oppositely disposed arcuate inlet and outlet ports formed in the top of said cylinder in proximity to said socket, ducts communicating with said ports and said cylinder at the opposite ends of the latter, a slide valve seat spaced from the top of said cylinder and having inlet and outlet 105 ports in alignment with first named ports, a rotary disk valve positioned between said cylinder and said slide valve seat for controlling the communication between the two sets of ports and an integral stem formed on 110 said disk valve to rotatably seat the same in said socket, said stem being apertured to communicate with said exhaust port and one of the ports controlled by said slide valve.

3. In a reversing valve mechanism including a piston cylinder having oppositely 120 disposed arcuate ports formed in the top thereof, ducts connecting said ports with said cylinders at either end of the latter, a disk valve formed with oppositely disposed arcuate grooves rotatably mounted on said cylinder and having oppositely disposed openings connecting said grooves with said cylinder ports, a slide valve seat positioned above said disk valve and means for partially rotating said valve to shift the com- 125 130

munication between said slide valve seat and said arcuate cylinder ports.

4. The combination in a reversing mechanism with a piston cylinder having oppositely disposed arcuate slots formed in the top thereof, of a disk valve rotatably mounted thereover and similarly formed with oppositely disposed arcuate grooves, a slide valve operating on said seat to control the motive fluid and means carried at one end of each of said disk valve grooves for establishing communication between said slide

valve seat and said cylinder ports and means for partially rotating said disk valve to transpose such communication.

15

In testimony whereof we have signed our names to this specification in the presence of two subscribing witnesses.
